UNITED STATES PATENT OFFICE.

JOSEPH GREENWOOD, OF PITTSFIELD, MASSACHUSETTS, ASSIGNOR OF ONE-HALF TO
PERRY E. MILLER, OF PITTSFIELD, MASSACHUSETTS.

SEWING-MACHINE.

1,115,926.

Specification of Letters Patent.

Patented Nov. 3, 1914.

Application filed April 9, 1914. Serial No. 830,791.

To all whom it may concern:

Be it known that I, JOSEPH GREENWOOD, a subject of Great Britain, residing at Pittsfield, county of Berkshire, and State of Massachusetts, have invented certain new and useful Improvements in Sewing-Machines, of which the following is a specification.

The invention relates to such improvements and consists of the novel construction and combination of parts hereinafter described and subsequently claimed.

Reference may be had to the accompanying drawings, and the reference characters marked thereon, which form a part of this specification. Similar characters refer to similar parts in the several figures therein.

Figure 1 of the drawings is a top plan view of an over-edge sewing-machine, partly broken away, showing the presser-foot-bar in horizontal section. Fig. 2 is an end elevation of the same. Fig. 3 is a front elevation of the same. Fig. 4 is a view similar to Fig. 1, illustrating the movement of the work-plate and the stitch-distending finger. Fig. 5 is a plan view of an edge portion of a piece of knitted fabric ornamented by over-edge stitching as applied by means of my invention.

This invention relates to a type of sewing-machine, commonly known in the art as the Merrow machine, adapted for forming an ornamental scalloped edge on knitted fabrics by means of a succession of groups of over-edge stitches crocheted together along their outer edges from group to group, the stitches in each group extending fanwise from points within the body of the fabric to points more or less outside of the edge of the fabric to produce the desired scalloped effect.

The principal object of the present invention is to accentuate the scalloped effect produced by a machine of said type.

Referring to the drawings wherein the invention is shown in preferred form, 1, represents the bed-plate of the machine; 2, the needle; 3, the looper or supplemental thread-carrier; and 4, the crochet-hook or latch-needle for crocheting the over-edge stitches together.

The work is fed along the bed-plate, 1, or a work-plate, 5, by toothed feed-bars, 6, which play through slots, 7, in the work-plate. The feed-bars, 6, are carried by a

slide, 8, adapted to reciprocate longitudinally in a slideway formed in a lever, 9, pivoted at 10, upon the base, 11, of the machine, said slide, 8, having a pin, 12, projecting out through a slot, 13, in the slideway-lever, 9, 60 which pin, 12, is engaged by the forked end, 14, of a lever, 15, fulcrumed at 16, upon the base of the machine. A pitman, 17, connects the intermediate portion of the lever, 15, with an eccentric, 18, fixed upon the 65 main drive-shaft, 19, upon which shaft is also fixed a pinion, 20, which engages a gear-wheel, 21, on the shaft, 22. The pinion, 20, is much smaller than the gear-wheel, 21, and causes the slide, 8, and feed-bars, 6, to be 70 rapidly and continuously reciprocated in the operation of the machine; but the feed-bars, 6, are effective to feed the work only when they are projected above the level of the work-plate, 5; and in the operation of the 75 machine the feed-bars, 6, are held depressed below the level of the work-plate, 5, during the formation of each group of stitches intended to form a scallop on the edge of the fabric, and is then projected for a brief 80 interval above the level of the work-plate to quickly cause a feed-movement of the work of approximately the length of a scallop. The feed-bars, 6, are thus raised at intervals 85 by means of a lever, 23, pivoted at 24, upon the base of the machine, said lever having a projecting finger or pin, 25, which engages a plate, 26, adjustably fixed upon the slideway-lever, 9, said lever, 23, having a laterally projecting finger or pin, 27, located in 90 the path of a cam, 28, fixed upon the shaft, 22. Except when the cam, 28, is in engagement with the pin, 27, the slideway-lever, 9, rests in the position in which it is shown in Fig. 2, in which position the feed-bars, 6, 95 are depressed below the level of the work-plate, 5; but at each engagement of the cam, 28, with the pin, 27, the lever, 23, slideway-lever, 9, and feed-bars, 6, are elevated, thereby forcing the teeth of the bars, 6, up above 100 the level of the work-plate, 5, into engagement with the work to feed the same.

The construction and manner of operation of the parts thus far described are old and well understood in the art; and further description of the same will be unnecessary, it being understood that the needle, looper and crochet-hook operate continuously to form and crochet together the over-edge stitches while the work is, at the completion of each 110

group of stitches, fed past the needle a distance equal to the length of a scallop.

In carrying out my invention, I provide for a reciprocating movement of the tapered 5 stitch-distending finger, 29, in a direction parallel with the direction of the feed-movement of the work; and for a reciprocating movement of the work-plate, 5, in a direction at right angles to the direction of the 10 feed-movement of the work.

In the preferred form of my invention shown in the drawings, the work-plate, 5, is mounted in a slideway, 30, in the bed-plate, 1, and has, depending from its under 15 side, a cam-follower, 31, which engages a cam-groove, 32, in a cam, 33, upon the shaft, 22.

The cam-groove, 32, is so formed that at 20 the beginning and end of each scallop formed by the machine, the work-plate, 5, will occupy its innermost position, as shown in Fig. 1, from which position it is gradually moved outward until one-half of the scallop is formed and then is gradually moved inward as the other half of the scallop is 25 formed. This reciprocating movement of the work-plate is sufficient to cause a slight reciprocating movement of the work sidewise, relatively to the presser-foot, 34, and needle, 2, which causes the needle to pass through 30 the work slightly nearer the edge of the work during the formation of the stitches at the middle of the scallop than during the formation of the stitches at the 35 ends of the scallop, thus permitting the stitches at the middle of the scallop to extend to a greater distance outside the edge of the fabric than they would if the work was not so shifted.

40 The tapered stitch-distending finger, 29, over which the stitches are formed is carried by a slide-bar, 35, which reciprocates in a slideway, 36, formed in the bed-plate, 1, parallel with the direction of feed-movement 45 of the work.

As a means for reciprocating the slide-bar, 35, I provide the same with an oblique slideway-groove, 37, adapted to receive an obliquely extending finger, 38, mounted 50 upon and carried by the work-plate, 5, whereby, as the work-plate, 5, is moved outwardly, the slide-bar, 35, and tapered finger, 29, will be moved inwardly to bring a wider part of the tapered finger, 29, opposite the needle; 55 and as the work-plate, 5, is moved inwardly the slide-bar, 35, will be moved outwardly to bring the narrower part of the tapered finger, 29, opposite the needle. The tapered finger, 29, thus acts to distend the stitches 60 formed over it, to a greater degree at the middle of each scallop than at the ends thereof, and in so doing, it coöperates with the movable work-plate, 5, to distend to the greatest degree the stitches, which, due to 65 the movement of the work-plate, 5, are in-

serted nearest to the edge of the fabric, with the result that the stitches at the middle of each scallop are made longer than the stitches at the ends of the scallop. The scallops are thus accentuated, made more 70 prominent, and are better defined than when the stitches are all of the same length and all pass through the fabric at the same distance from its edge, in which case the scalloped effect is due entirely to the fan-wise 75 arrangement of the stitches.

The oblique finger, 38, preferably has a slotted-shank, 39, which is attached to the work-plate, 5, by means of a set-screw, 40, whereby the position of the finger relatively 80 to the slide-bar, 35, can be adjustably varied to properly time the movement of the tapered finger, 29, to accord with the movement of the work-plate, 5.

It will be understood that the movable 85 tapered, stitch-distending finger, 29, and the movable work-plate, 5, each of itself tends to accentuate the scalloped formation. By their combined use, however, I am able to obtain greater accentuation of the scalloped formation than with either the movable finger or the movable plate used alone. 90

For certain purposes of the invention, the 95 stitch-distending tapered finger may be reciprocated in any known manner; and the work-plate, 5, or device which engages the work and shifts the work sidewise of the needle, may be operated in any known manner.

I have shown in the drawings a looper, 3, 100 which in certain machines of this general type carries a second thread, and is known as a supplemental thread-carrier; but I do not wish to be limited to the use of such a looper or supplemental thread-carrier, as 105 for certain purposes of my invention any known mechanism for forming over-edge stitches and crocheting them together may be employed in combination with my improved means for accentuating the scallops 110 formed by the machine.

What I claim as new and desire to secure by Letters Patent is—

1. In a machine of the class described, and in combination, over-edge-stitch-forming 115 mechanism, including a needle and a crochet-hook; means for intermittently feeding the work upon the completion of each group of stitches; a work-engaging member movable transversely of the direction of feed-movement of the work; and means for automatically imparting to said member a reciprocating movement in the interval between successive feed-movements of the work. 120

2. In a machine of the class described, and in combination, over-edge-stitch-forming mechanism, including a needle and a crochet-hook; means for intermittently feeding the work upon the completion of each 130

- group of stitches; a pair of work-engaging members comprising a work-plate and a presser-foot, one of said members being movable relatively to the needle transversely 5 of the direction of the feed-movement; and means for automatically imparting to said movable member a reciprocating movement in the interval between successive feed-movements of the work.
- 10 3. In a machine of the class described, and in combination, over-edge-stitch-forming mechanism, including a needle and a crochet-hook; means for intermittently feeding the work upon the completion of each 15 group of stitches; means for imparting to the work a sidewise reciprocating movement relatively to the needle in the interval between successive feed-movements of the work; a tapered stitch-distending finger over 20 which the stitches are formed; and means for automatically imparting to said finger a reciprocating movement in the interval between successive feed-movements of the work.
- 25 4. In a machine of the class described, and in combination, over-edge-stitch-forming mechanism, including a needle and a crochet-hook; means for intermittently feeding the work upon the completion of each group 30 of stitches; a work-supporting plate capable of movement at right angles to the direction of feed-movement of the work and provided with openings to receive the said work-feeding means; and means for automatically imparting to said plate a reciprocating movement in the interval between successive feed-movements of the work.
5. In a machine of the class described, and in combination, over-edge-stitch-forming mechanism, including a needle and a crochet-hook; means for intermittently feeding the work upon the completion of each group of stitches; a work-supporting plate capable of movement at right angles to the direction of feed-movement of the work and provided with openings to receive the said work-feeding means; and means for automatically imparting to said plate a reciprocating movement in the interval between successive feed-movements of the work; a movable, tapered stitch-distending finger over which the stitches are formed; and a member carried by said work-plate engageable with said tapered stitch-distending finger to reciprocate the finger in accordance with the reciprocating movement of the work-plate.

In testimony whereof, I have hereunto set my hand this 3rd day of April, 1914.

JOSEPH GREENWOOD.
